2,619,063

ARMATURE SOLDERING FURNACE

Hjalmar A. Anderson, Riverside, Ill., assignor to
 Sunbeam Corporation, Chicago, Ill., a corporation of Illinois

Application November 12, 1949, Serial No. 126,865

3 Claims. (Cl. 113—59)

1

This invention relates to soldering furnaces and more particularly to furnaces for soldering armature conductors to their respective commutator bars.

Heretofore the soldering of armature conductors or leads to their respective commutator bars has been in general a manual operation, particularly in large size motors. To effect these connections the assemblyman individually positions each conductor in proper relation with its respective commutator bar. Where the commutator bars are provided with slotted risers the ends of the conductors are disposed in the slots. When the conductors are in their proper position with respect to the commutator bars the assemblyman heats up the portion of each commutator bar that is to form the connection or joint and the conductor to the proper soldering temperature by a conventional soldering iron. When the parts are at the proper temperature solder is applied in a conventional manner. This method of effecting soldered connections between conductors and commutator bars takes a considerable amount of time and is hazardous to the assemblyman because if he attempts to make a second soldered connection before the first has cooled sufficiently he is apt to be severely burned when he pre-positions a conductor with the adjacent commutator bar. This manual method of effecting connections on armatures is quite costly and is in general an unsatisfactory method of effecting connections.

Accordingly, an object of the invention is to provide a novel furnace construction that is capable of simultaneously effecting a soldered connection between all of the armature conductors and their respective commutator bars.

Another object of the invention is to provide a novel furnace construction for soldering armature conductors to commutators, that is relatively free of hazards to operating personnel, that requires a minimum of manual manipulation in effecting the soldered connections, that greatly reduces the time required to make such connections and that permits of making the connections at a relatively low cost.

Another object of the invention is the provision of a furnace of the above character having novel means for supporting an armature to position the portions of the commutator bars to which the conductors are to be attached so that these portions of the commutator form one wall of a solder distributing chamber capable of retaining solder adjacent these portions at a temperature to effect a soldered connection between the conductors and the commutator bars.

Another object of the invention is the provision of a furnace of the above character, in which a solder distributing chamber for retaining solder is formed by portions of the furnace and portions of the commutator bars to which the conductors

2

are to be secured, having novel means for supplying liquid solder to the chamber at a preselected temperature for a preselected time to effect soldered connections between the commutator bars and conductors.

Another object of the invention is the provision of a furnace of the above character having novel means for controlling the flow of solder to and from a solder storage chamber and the solder distributing chamber.

Another object of the invention is the provision of a furnace of the above character, in which a solder distributing chamber for retaining solder is formed by portions of the furnace and portions of the commutator bars to which the conductors are to be attached having means for supplying molten solder to the solder distributing chamber having novel means for limiting the level of solder in the solder distributing chamber whereby to effect a good soldered connection between the bars and the conductors while at the same time preventing damage to the insulation on the conductors.

Other objects and advantages of the invention will become apparent from the following detailed description taken in connection with the accompanying drawings, in which—

Figure 1 is a side elevational view of a furnace embodying the present invention with portions cutaway to show a solder displacement plunger in its retracted position;

Fig. 2 is a fragmentary sectional view through one of the cubical portions of the furnace showing the solder displacement plunger in its lower operating position;

Fig. 3 is an enlarged fragmentary vertical sectional view showing details of construction of the support means for the armature;

Fig. 4 is a plan view of the furnace with portions cutaway to show details of construction;

Fig. 5 is a sectional view taken substantially along the line 5—5 in Fig. 4;

Fig. 6 is a wiring diagram of an electrical control circuit for the furnace;

Fig. 7 is a vertical sectional view of a modification of the invention;

Fig. 8 is a sectional view showing a modification of an adapter ring, and

Fig. 9 is an enlarged side elevation view of the electrode holder shown in Fig. 7.

Referring now to the drawings the invention is shown embodied in a furnace for effecting a soldered connection between the conductors or leads 11 of an armature 12 and the commutator bars 13 of a commutator 14. For purposes of illustrating the invention each commutator bar 13 comprises a body 16 and a riser 17 at one end of the body. The riser 17 is formed by spaced side members that define a slot for receiving the conductor 11 as best seen in Fig. 3. The commutator bars 13 are assembled as by spaced V rings

18 and 19 on a shaft 21 so that the risers define an annular shoulder portion 22 extending outwardly from the periphery of the body portion of the commutator 14. It is to be understood that the furnace disclosed herein may also be used for soldering the conductors to the commutator bars in commutators having other constructions.

While the body of the furnace may assume many different shapes as will be apparent to those skilled in the art, for purposes of illustration it is shown in Fig. 4 as comprising a cylindrical shaped central portion 24 and a pair of cubical portions 26 on diametrically opposed sides of the central portion. The central portion 24 and the cubical portions 26 are mounted on a bottom 27 supported on a base 28. Each of the cubical portions 26 is defined by spaced upstanding members 29 interconnected at opposite ends by spaced members 31 and 35. The central portion includes arcuate-shaped members 32 rigidly secured at opposite ends to the upstanding members 29 as best seen in Fig. 4. With this construction the arcuate members 32, the side members 29 and the bridging members 31 define an outer peripheral wall for the furnace. Disposed between the arcuate members 32 and in concentric relation therewith is an upstanding cylindrical sleeve member 33 defining an inner wall of the furnace, the latter wall being shorter than the outer wall. The upwardly facing opening of the cylindrical member is sufficiently large to form a mouth shaped to receive the commutator end of the armature 12. The tops of the inner and outer walls are interconnected by a member 34 shaped to define with the outer wall an upstanding portion 36 and with the inner wall an upstanding portion 37, a bridging portion 38 between the upstanding portions 36 and 37 to form with said upstanding portions 36 and 37 a channel or annular recess 39 extending around the opening of the cylindrical member 33, and a flange 41 resting on top of the cylindrical member 33 and partially overlying the mouth of the upwardly facing opening therein. The annular channel 39 is shaped to receive suitable heating elements 42 such as the resistance units shown in Figs. 1 and 3 resting on the bridging portion 38 and connected to terminals 43 and 44 for ready connection to an external source of power. As shown the terminals are mounted on a suitable support 45 affixed to one side of the central portion 24. Rock wool or other suitable insulating material may be disposed between the inner and outer walls as shown in Fig. 5 for insulation purposes. Preferably a partition 50 is disposed between the inner and outer wall portions at a point spaced upwardly from the bottom 27 to support the rock wool beneath the annular chamber 39. An annular channel shaped member 46 is attached to the interior of the sleeve member 33 beneath the flange 41 to provide a support therefor and a mounting for an armature support flange 47 extending inwardly of the opening in the cylindrical member 33. Annularly spaced uprights 48 adjacent the inner wall of the body extend between the bottom 27 and the channel member 46 for reinforcement purposes.

In this embodiment of the invention the armature 12 is arranged to be mounted on the flange 47 in an upright manner as shown in Figs. 1 and 3. For this purpose an adapter plate or ring 49 is provided having an opening 51 of substantially the same size as the diameter of the commutator 14 and a shoulder portion 52 shaped to abut against the shoulder portion 22 of the com-

mutator. The adapter ring 49 is of a diameter larger than the opening in the flange 47 so that when the adapter ring 49 is in the position shown in Fig. 3 the adapter ring overlies the flange 47 to be supported thereby. The flange 47 and adapter ring 49 are preferably dimensioned and shaped so that the risers 17 and conductors or leads 11 are positioned in spaced relation to the upstanding portion 36 and together with it and the upstanding portion 37 define a solder distributing chamber 54 (see Fig. 3) encircling the commutator 14. A gasket 55, in the form of a ring having a circular cross section, is disposed between the flange 47 and a shoulder 56 on the adapter plate 49 to prevent leakage of solder from the solder distributing chamber 54.

Disposed in each of the cubical portions 26 is a solder storage pot or well provided with means for transferring the solder from the pot to the distributing chamber 54 so that molten solder may be applied to the connections between the commutator bars 13 and their respective conductors 11. As shown herein each solder pot is in the form of a container 57. At its lower end each container comprises three compartments 58, 59 and 61 as best seen in Fig. 4, and at its upper end each container has a single compartment in alignment with and forming an upper part of the compartment 59. The sides of the container are spaced from the sides of the cubicals and rock wool (see Figure 1) or the like is disposed between the respective walls of the cubical and the container for insulation purposes. Suitable means for heating the solder may be disposed in the outer compartments 58 and 61. In this instance the heating means comprises a resistance unit 62 having a generally U shape with the bridging portion spanning the lower end of the compartment 59 and its leg portions extending upwardly through the compartments 58 and 61 and terminating at terminals 63 and 64 mounted on top of the body on opposite sides of the container 57 to be readily accessible for connection to an external source of power. A charge chute 66 opening on the top of the body is provided for introducing bar solder or the like to the container 57 through an opening 67 formed in the container 57 adjacent its bottom. A pivotally mounted cover 68 normally closes the upper end of the chute 66 as shown in Figure 1. To introduce solder into the chute the cover 68 is moved to the dotted line position shown in Figure 1. A solder displacement plunger 71 is mounted in the container 57 for movement between a position in which it is in the upper end of the compartment 59 and a position in which it is disposed in the lower end of the compartment 59. In the latter position the plunger 71 forces the solder in the container 57 into the solder distributing chamber 54 through an opening 72 formed in the side walls of the container 57. Vertically extending strips 75 (see Fig. 4) secured to the walls defining the compartment 59 serve to guide the plunger 71 in its up and down movement.

Suitable means is provided for controlling the movement of each plunger 71. In this instance each plunger is connected to one end of a piston, not shown, of a fluid operated unit 73 as by a rod 74 extending through an opening in the top of the container 57. Each fluid operated unit 73 is mounted on an upstanding bracket 76 rigidly secured to the top of the body as by welding. Vertically spaced brackets 77 engage opposite ends of each cylinder 78 of each fluid operated

unit to secure the latter on their respective brackets 76 in a conventional manner. The units are positioned to be in overlying relation with their respective containers 57. The fluid operated units 73 are under the control of a suitable control valve unit 79. The latter is connected to the upper end of each cylinder 78 by a conduit 81, to the lower end of each cylinder 78 by a conduit 82 and to a suitable pressure fluid source by conduit 83.

The control valve unit 79 may be manually operated, mechanically operated, electrically operated, or operated by combinations of the foregoing. For purposes of illustrating the invention the control valve unit 79 is an electrically operated unit. Since many suitable solenoid operated valves are commercially available and their constructions are so well known the details of construction of the control valve unit 79 are not shown herein. For purposes of showing the operation of the furnace however the solenoid coils of the control unit 79 are indicated by the numerals 84 and 85 in the electric circuit shown in Fig. 6. The control unit 79 is arranged so that when one of the solenoid coils is energized the fluid operated units 73 are connected to the pressure fluid supply so that the solder displacement plungers 71 are forced downwardly to assume the position shown in Fig. 2. When the other solenoid coil is energized the fluid operated units 73 are connected to the pressure fluid supply so that the plungers 71 are urged to their upper positions to assume the position shown in Figure 1.

In Fig. 6 there is shown one embodiment of an electric control circuit that may be used to control the operation of the furnace. This control circuit is arranged so that by pressing a single push button to initiate operation of the circuit the furnace goes through its complete cycle of operation and returns the moving parts to their initial position at the conclusion of the soldering operation so that the furnace is ready for a subsequent soldering operation.

The control equipment for this circuit includes relays 1R, 2R and 3R, a timing relay TR, a fused double pole knife switch 99 for connecting the control circuit to a source of power, a switch 91 in the form of a push button, normally closed limit switches 92, one associated with each plunger 71 and arranged to be actuated when the plunger is in its upper position, a transformer 94 and a liquid level control unit 96.

The switches 92 in this instance are mounted on the brackets 76 to have their actuating plungers 85 project downwardly. Since the actuating mechanism is the same for each switch only one will be discussed in detail. The actuating mechanism includes a slideable pin 90 arranged to engage the plunger 85. As shown the pin 90 is mounted to project through a passageway formed in a pin guide and support bracket 95 rigidly attached to the bracket 76 in spaced relation to the switch 92. At its extreme lower end the pin 90 is formed with an arm 100 shaped to engage a collar 105 rigidly attached to the rod 74 of the fluid operated unit so that when the plunger 71 is in its upper position the switch 92 is opened.

The control unit 96 comprises a pair of electrodes 97 and 98. The electrode 97 is mounted on an arm 99 rigidly attached to the upright 76, not shown, so that the lower end of the electrode is disposed in the solder distributing chamber 54. The electrode 98 is slidably mounted on an arm 101, rigidly attached (not shown) to the upright

76 to be disposed in the solder distributing chamber 54 so that the lower end of the electrode 98 may be raised or lowered. A spring 102 is disposed between the arm 101 and the head 103 on the electrode 98. The spring is biased so that it tends to urge the electrode upwardly. Overlying the head 103 is an eccentric cam 104 rotatably mounted on an arm 106 rigidly attached, not shown, to the bracket 76. The position of the cam 104 may be adjusted by a handle 107. By changing the position of the cam with this construction the lower end of the electrode 98 may be moved up or down. Thus the level of solder in the chamber 54 may be varied to accommodate different sizes of commutators.

Assume that the heating elements 42 and 62 are in operation to maintain the solder in a molten state, the bottom portion of the container 57 is filled with solder, that the armature 12 is in the position shown in Figure 1 and that the switch 89 is connected to power lines L1 and L2 respectively. To start the furnace so that it automatically goes through one soldering cycle the operator presses the push button 91 of the self-return type to complete a circuit from the line L1 through the contacts of the switch 91 to a coil 108 of the relay 1R back to the line L2. In operating, the relay 1R closes its normally open contacts 1R1 to provide a locking circuit for itself. The latter may be traced from the line L1 through the normally closed contacts of the timing relay TR through the contacts 1R1, the coil 108 to the line L2. Thus the relay 1R is held operated after the start switch 91 is released by the operator and an operating cycle of the control circuit is initiated. At its normally open contacts 1R2 the relay 1R in operating closes a circuit for energizing the coil 84 of the solenoid valve in the control unit 79. This circuit may be traced from the line L1 through the contacts 1R2 the coil 84 back to the line L2. As a consequence the valve is energized so that pressure fluid is introduced into the upper ends of the cylinders 78 of the pressure fluid units 73 to cause downward movement of the solder displacement plungers 71. Solder flows from the containers 57 through the openings 72 into the solder distributing chamber 54. Solder flows into the chamber 54 until the level therein corresponds to the preselected setting of the liquid level control 96. The level of solder for each type of armature will vary depending on the length of the commutator bars, the risers, location of the insulation on armature conductors, position at which the soldered connection is to be made with the commutator bar where risers are not employed and the like factors. When the level of solder in the chamber 54 reaches the preselected level, the solder bridges the electrodes 97 and 98 to close an electric circuit to a coil 109 of the relay 3R. The latter circuit includes the electrode 97, the coil 109, the secondary winding 111 of the transformer 94 and the electrode 98. The primary winding 112 of the transformer 94 is connected in a circuit which includes the line L1, the primary winding 112, one side of the normally open contacts 3R1 and the line L2. In operating the relay 3R closes a circuit through its normally open contacts 3R1 to energize a coil 113 of the timing relay TR. Upon energization of the coil 113 the relay TR operates to open its normally closed contacts TR1 to open a point in the holding circuit of the coil 108 of the relay 1R. Upon deenergization of the coil 108 the contacts 1R1 open to open another point in the holding circuit

for the coil 108 and the contacts 1R2 open to open the circuit to the coil 86 of the control valve unit 79.

While the solder is maintained at the preselected level in the chamber 54 it flows to the connections between the armature leads and the commutator bars. The solder is maintained at a preselected temperature by the heating elements 42 and 62 to obtain good flow characteristics and for a preselected time to effect heating of the soldered parts and thereby insure positive soldered connections. After the selected time interval the relay TR operates to close its normally open contacts TR2. In so doing it closes a circuit to the coil 114 of the relay 2R which may be traced from the line L1 through the normally open contacts TR2, the coil 114, to the line L2. Upon energization of the coil 114 the relay 2R operates to close its normally open contacts 2R1 and its normally open contacts 2R2. At its contacts 2R1 the relay closes an obvious holding circuit for the coil 114. The latter may be traced beginning with the line L1 through the limit switches 92, the contacts 2R1, the coil 114, and ending at the line L2. At its contacts 2R2, the relay 2R in operating closes an obvious circuit to energize the coil 86 of the control unit 79. Energization of the latter directs pressure fluid to the bottom of the cylinders 78 and thereby effects upward movement of the displacement plungers 71. Solder from the distributing channel 54 flows back into the solder containers 57. As soon as the level of the solder gets below the electrode 98 the circuit to the coil 109 of the relay 3R is broken and the coil 109 is de-energized. Upon de-energization of the coil 109 the relay 3R operates to open its contacts 3R1. Upon opening its contacts 3R1 the circuit to the coil 113 of the relay TR is broken and it becomes de-energized. Upon de-energization of the coil 113 the relay TR operates to close its normally closed contacts TR1 to close a point in the holding circuit for the coil 108 and to open normally open contacts TR2 to open one energizing circuit of the coil 114 of the relay 2R. Upward movement of the plungers 71 continues until both limit switches 92 are actuated by their respective actuating mechanisms acting between the collar 105 and the plungers 85. Actuation of both limit switches opens the circuit to the coil 114 of the relay 2R and effects de-energization thereof. Upon de-energization of the coil 114 the relay 2R operates to open its normally open contacts 2R1 to open a holding circuit for the coil 114 and to open its normally open contacts 2R2 to open a point in the circuit to the coil 86 of the control unit 79 to de-energize the coil 86.

Under these conditions the armature may be removed and replaced by another and the above process of soldering the connections repeated. To accommodate different diameters of commutators the adapter plates for different sized armatures should have openings shaped to accommodate the size of the armature being soldered. Normally some solder spills or leaks between commutator bars or between the gasket 55 and the adapter plate 49 or the armature support flange 47. This may be collected in a pull drawer 121 or the like disposed in an opening at the bottom of the body as shown in Figure 1. To guard against splattering of solder on personnel or equipment a cover 122 (see Fig. 4) may be provided on the body to overlie the solder distributing channel 54.

The foregoing furnace construction has many advantages. The furnace is simple to construct

and it insures a uniform and simultaneous soldering of all joints between the commutator bars and the respective armature containers. Too, the soldered connections may be made quickly and there is a minimum of manual manipulation in effecting the soldered connections.

In Fig. 7 there is shown a modified form of the invention in which the overall height of the furnace is less than that of the embodiment shown in Figs. 1-6. In this embodiment of the invention the body 131 of the furnace has the same general configuration as that described for the embodiment shown in Figs. 1-6 and includes a centrally disposed upstanding sleeve 132 open at its upper end and shaped to receive the commutator end of an armature or a similarly shaped workpiece, an annular solder distributing chamber 133 encircling the sleeve, a heating element 134 disposed in the solder distributing chamber, an annular shoulder 136 on the interior of the sleeve for supporting an adapter ring 138 shaped to support the armature in a position such that the portion of the commutator to be connected with the conductors defines a portion of the wall of the solder distributing chamber, a gasket 137 between the support ring 138 and the shoulder 136 and a solder storage container or well 139 on each side of the sleeve 132. Each solder storage chamber 139, only one being shown in this instance, is in communication with the solder distributing chamber 133 through an opening 141 (see dotted lines in Fig. 7) formed in a wall between the well 139 and the annular distributing chamber 133. A plunger 142 is mounted for reciprocation in each well 139 to control the flow of solder from the well 139 to the solder distributing chamber. A deflector 143 causes the solder flowing through the opening 141 to flow uniformly about the solder distributing chamber 133.

In this embodiment of the invention each plunger 142 is caused to move between opposed vertical positions by a pair of pressure fluid operated units 146 mounted on opposite sides of a body of the furnace and under the control of a conventional control unit 145 mounted on the body 131. Each pressure fluid unit includes a cylindrical housing 147, a piston, not shown, reciprocably mounted therein, and a vertical piston rod 148 attached to the piston and movable in response to movement thereof. At their upper ends the rods 148 of each pair of pressure fluid units are pivotally connected to a cross arm 149 overlying each plunger 142. Each cross arm 149 is rigidly attached intermediate its ends to the associated plunger 142 by a suitable connection 151. The pressure fluid units 146 operate in a conventional manner such that when pressure fluid is introduced into the tops of the cylinders 147 by the control unit 145, the associated pistons, and in turn the plunger 142, move downwardly as viewed in Fig. 7 and when pressure fluid is introduced to the bottoms of the cylinders 147, assuming the pistons are in their lowermost position, the associated pistons and the plunger 142 move upwardly. Suitable spaced guide wheels 152 attached to the cross arm 149 engage vertical rigid rails 153 to guide each plunger in its reciprocable movement. The vertical rails are rigidly attached to the body at their lower ends and are interconnected by a bridging member 157 at their upper ends. As shown, the guide wheels are mounted in a suitable manner on a truck 154 secured to the crosspiece 149.

As shown in Fig. 7 a limit switch 158 is mount-

ed on the underside of the bridging member 157 to be engaged by the crosspiece 149 when the latter is in its upper position. To facilitate the collection of waste solder at the bottom of the sleeve 132 a funnel-shaped member 159 is disposed in the sleeve to have its large opening facing the upper end of the sleeve and its small end overlying a drawer 161. Any solder spilled or wasted during the soldering process is thus directed into the drawer 161. The latter may be readily withdrawn from the body of the furnace so that the waste solder can be used over.

Figs. 7 and 9 show an alternate electrode support construction for holding or supporting the electrodes 162. In this instance each electrode is held by a holder comprising a link 163 having a split collar 150 at one end defining a vertical opening for receiving one electrode 162, and a link 164 formed with a collar 160 having an opening for receiving a vertical post 167 which projects outwardly from the mounting pad 168 secured to the body 131. Any conventional means, such as a set screw 170, may be used to secure the collar 160 to the post 167 at a desired adjusted elevation. Any number of links 165 may be used between the links 163 and 164 to interconnect the latter and to locate the electrodes 162 in a desired horizontal position so that they are disposed in the solder distributing chamber 133. The electrode 162 may be connected with a control unit or circuit, such as described hereinbefore through leads 175 suitably connected to the electrode holders as shown.

Fig. 8 shows a modified construction for an adapter ring 171 for supporting an armature. In this modification the adapter ring 171 is formed with a shoulder 172 shaped to seat on a gasket 173 supported on a shoulder 174 on the inner sleeve 175 in a manner described hereinbefore adjacent a solder distributing chamber 176. The adapter ring 171 is formed with a vertically extending chamber 177 defined by spaced walls 178 and 179. Disposed within the chamber 176 is a heating element 181. The ends of the heating element 183 (one only being shown) project through the bottom wall 182 of the chamber 177 and are adapted to be connected to an electrical terminal connection 188 connected to a suitable power source 187 through the power leads 184.

While I have shown several embodiments and modifications of my invention, it will be understood that I do not wish to be limited thereto since many modifications may be made and I therefore contemplate by the claims to cover such modifications as fall within the true spirit and scope of my invention.

I claim:

1. In a furnace for soldering the conductors of an armature to their respective commutator bars, the combination of a body having an upwardly facing opening shaped to receive the commutator end of an armature and spaced upstanding portions on its upper edge encircling said opening, the outer of said upstanding portions extending upwardly farther than the inner portion, an annular flange adjacent the inner upstanding portion extending inwardly of said opening, an annular adapter plate overlying said annular flange shaped to be supported by said annular flange and shaped to support an armature in said opening in a position to have the portion of the bars connected to the armature conductors in spaced relation to the outer upstanding portion to define

with said upstanding portions a solder distributing chamber encircling the commutator, a ring disposed between the flange and the adapter plate to form a seal at the bottom of the chamber, and means for supplying solder to said chamber at a temperature to simultaneously effect a soldered connection between all the conductors and their respective commutator bars.

2. In a furnace for soldering the conductors of an armature to their respective commutator bars, the combination of a body having an upwardly facing opening shaped to receive the commutator end of an armature and an upstanding portion on its upper edge encircling said opening, means for supporting an armature in said opening in a position to have the portion of the bars to be connected to the armature conductors in spaced relation to the upstanding portion to define therewith a solder distribution chamber encircling the commutator, means for supplying molten solder to said chamber in a fluid state, means associated with said distributing chamber for maintaining the solder in said fluid state, electric control means including at least one electrode extending into said solder distribution chamber for limiting the liquid level of solder in said chamber at a level herein the portions of the conductors to be soldered to the commutator are submerged in solder to simultaneously effect soldering of all armature leads with their respective commutator bars.

3. In a furnace of the solder displacement type for simultaneously soldering a plurality of parts to a workpiece which furnace employs interchangeable adapter rings for supporting various sizes of said workpiece and wherein the solder must flow over the particular adapter ring employed in the furnace at any one time, an adapter ring for supporting a workpiece of relatively small size comprising spaced concentrically arranged inner and outer annular members, said inner member having its upper edge shaped to form a shoulder for supporting the workpiece, means for interconnecting the bottom edges of said inner and outer members to define with said members an upwardly facing open annular chamber, a flange on said outer member shaped to be supported on the furnace for supporting the adapter ring and workpiece and heating means disposed in said chamber whereby said adapter ring is heated so as not to cool solder flowing over the same.
